UNITED STATES PATENT OFFICE.

ROLAND ONFFROY, OF NEW YORK, N. Y., ASSIGNOR TO UNITED STORES ASSOCIATION, OF NEW YORK, N. Y., A CORPORATION OF NEW YORK.

DESIGN FOR A LETTER-HEAD OR SIMILAR ARTICLE.

42,228.

Specification for Design.

Patented Feb. 27, 1912.

Application filed October 26, 1911. Serial No. 656,990. Term of patent 14 years.

To all whom it may concern:

Be it known that I, ROLAND ONFFROY, a citizen of the United States of America, and residing in the borough of Manhattan, city, county, and State of New York, have invented a new, original, and ornamental Design for Letter-Heads or Similar Articles, of which the following is a specification, reference being had to the accompanying drawing, forming a part thereof.

The figure is a plan view of a letter head showing my new design.

I claim:

The ornamental design for a letter head or similar article, as shown.

ROLAND ONFFROY.

Witnesses:

PATRICK EGAN,
J. DEAN BARNES.
